US00D800548S

(12) **United States Design Patent** (10) **Patent No.:** **US D800,548 S**
(45) **Date of Patent:** **** Oct. 24, 2017**

(54) **CLOSEABLE CONTAINER**

(71) Applicant: **Inno-Pak, LLC**, Delaware, OH (US)

(72) Inventors: **Jonathan D. Sill**, Powell, OH (US);
Steven A. Mayer, Indianapolis, IN (US)

(73) Assignee: **Inno-Pak, LLC**, Delaware, OH (US)

(**) Term: **15 Years**

(21) Appl. No.: **29/567,062**

(22) Filed: **Jun. 6, 2016**

(51) LOC (10) Cl. **09-03**

(52) U.S. Cl.

USPC **D9/418**

(58) **Field of Classification Search**

USPC D9/414, 418-422, 431-433, 499;
D7/612; D19/91

CPC B65D 5/4204

See application file for complete search history.

(57) **CLAIM**

The ornamental design for a closeable container, as shown and described.

DESCRIPTION

FIG. 1 is a perspective view of a closeable container showing a new design;

FIG. 2 is a front view thereof;

FIG. 3 is a rear view thereof;

FIG. 4 is a left side view thereof, the right side being a mirror image;

FIG. 5 is a top view thereof;

FIG. 6 is a bottom view thereof;

FIG. 7 is a perspective view of the closeable container showing the closeable container in an open configuration;

FIG. 8 is a perspective view of a closeable container in accordance with a second embodiment of the invention;

FIG. 9 is a front view thereof;

FIG. 10 is a left side view thereof, the right side being a mirror image;

FIG. 11 is a top view thereof; and,

FIG. 12 is a perspective view of the closeable container showing the closeable container in an open configuration. The broken lines shown in the figures are included for the purpose of illustrating perforations and form part of the claimed design.

1 Claim, 10 Drawing Sheets
